UNITED STATES PATENT OFFICE.

JOHN C. KOPF, OF BELLEVUE, PENNSYLVANIA, ASSIGNOR TO THE DUFF MANUFACTURING COMPANY, OF PITTSBURGH, PENNSYLVANIA, A CORPORATION OF PENNSYLVANIA.

SELF-LOWERING SCREW JACK.

1,411,282.

Specification of Letters Patent.

Patented Apr. 4, 1922.

Application filed August 2, 1920. Serial No. 400,801.

To all whom it may concern:

Be it known that I, JOHN C. KOPF, a citizen of the United States, and resident of the borough of Bellevue, in the county of 5 Allegheny and State of Pennsylvania, have invented a new and useful Self-Lowering Screw Jack, of which the following is a specification.

This invention relates to self-lowering screw-jacks; that is to say jacks having lifting screws beyond the angle of repose, and mechanism connected therewith whereby the loaded jacking member can be allowed to run down under the control of braking means.

Such jacks as heretofore constructed have involved more or less complication of mechanism, because of the element of danger in lowering heavy loads in this manner; which mechanism has almost universally been carried in an enlarged head of the vertically movable jacking member, the jack as a whole thus being cumbersome and topheavy and liable to bending of its screw by canted load.

The object of the present invention is to provide a self-lowering jack which shall be safe, simple, stable, convenient to handle and operate, and inherently protected by its mechanism and general organization against injury, both from improper jacking and the vicissitudes of lowering.

In the accompanying drawings illustrating the invention:

Figure 1 is a rear elevation of a jack embodying the invention, the outer portion of 35 the lifting shaft being sectioned;

Fig. 2 is a vertical section taken in the plane of the axes of the lifting screw and lifting shaft, which members are seen in elevation;

Fig. 3 is an enlarged vertical section on the line 3—3 of Fig. 2;

Fig. 4 is an enlarged vertical section on the line 4—4 of Fig. 1;

Fig. 5 is an enlarged perspective view of 45 the brake-band;

Fig. 6 is an enlarged perspective view of the thrust-collar;

Fig. 7 is an enlarged front elevation of the drum;

Fig. 8 is an enlarged view of the drum partly in side elevation and partly in section; and

Figs. 9 and 10 are enlarged perspective views of two of the disks.

The jack has a closed housing frame, comprising an expanded supporting base 1 with a hollow standard 2 rising therefrom and an annex 3 at the back or side, near the bottom. A cylindrical ram 4 having a small head 5 is contained within the standard in the lowered condition, and has a sliding bearing in a rigid guide 6 in the top of the standard. The ram is also hollow to accommodate the vertical steep-pitch screw 7, which is supported by a ball-bearing 8 upon the top of the base proper. The vertically-movable ram or jacking member is held against turning by a key 9 in the upper portion of the standard cooperating with a vertical groove 10 in the ram, and at its lower end the ram has a nut 11 to cooperate with the screw. .

A horizontal main operating shaft 12 is journaled in a bearing 13 in the outer wall 14 of the annex 3, and is geared to the screw by a bevel pinion 15 on its inner end meshing with a bevel gear 16 keyed to the lower portion of the screw. A worm wheel 17 is fixed by a key 18 to the operating shaft, behind the bevel pinion 15 and between the same and the inner end of the bearing 13, which projects for a substantial distance within the annex. Said worm wheel meshes with a worm 19 on a shaft 20, the axis or shaft of the worm being transverse to the main operating shaft 12. The shaft 12, the outer portion of which will be understood to be formed for operation by the usual lever and pawl rocker, may be termed the lifting shaft, and the worm, or its axis, the holding and lowering shaft. The worm and worm-wheel are of sufficiently steep pitch, so that, like the screw, they will run down by gravity under the action of the load, the worm-wheel driving the worm. A portion of the action of the load which is transmitted to the worm produces an end-thrust therein, which acts toward the left in Fig. 3 of the drawings. To hold and release the worm, and therefore the jacking member, means are provided which will now be described.

In the particular construction illustrated, the worm 19 and parts associated upon its axis are housed in a transverse chamber 21 merging with the top of the annex and the back of the standard, and having its outer portion 22 enlarged to form a brake-chamber. Said brake-chamber has a large cir-

cular entrance 23 at the outer end, which is closed by a bolted-on cover-plate 22^a, having a circular alining shoulder 24 fitting the entrance. In the center of this cover plate, 5 and in the remote end wall of the chamber 21, are journal bearings 25, 26 for the journal ends of the worm shaft 20. On said shaft, between the worm and the inwardly projecting bearing 25 of the cover-plate, is a 10 collection of flat, smooth-faced friction disks 27, 28, of which the set 27, is coupled to the worm-shaft for rotation therewith, while the set 28, in this particular instance, is engaged with a drum 29. Thus positioned, the 15 pile of friction elements is adapted to be compacted and locked by the end-thrust of the worm under load. The combined friction of the surfaces is such as to insure safe holding under any conditions, but need not be 20 excessive, since the pressure producing locking is automatically adjusted to the load. With such a device there is a desirable momentary cushion slippage when arresting the momentum of lowering.

25 The disks 27 are coupled to the shaft in respect to rotation, with capacity for slight longitudinal movement thereon, by means of longitudinal ribs or integral splines 30 pinched out of an intermediate portion of 30 the shaft, and cooperating notches 31 at the sides of the central holes 32 whereby the disks are strung upon the shaft. The disks 28 have larger central openings 33 permitting the shaft to turn therein, and are of 35 larger outside diameter than the disks 27, so that they may be formed with external notches 34 for engagement with internal longitudinal ribs 35 on the sides of the drum 29.

40 The end-thrust of the worm is exerted upon the disks through a collar or spacer 36, and is solidly sustained by the bearing 25. The drum has a back wall 37, which is interposed between the disks and the end 45 abutment of the bearing 25, and formed with an end-thrust bearing boss 38 for contact with the latter. The said wall of the drum is further provided with a central bearing opening 39 whereby it is supported on a 50 smooth portion of the shaft, in addition to which the open forward part of the drum has relative rotary bearing on a circular flange 40 on the thrust-collar 36, the entrance of the drum being formed for this 55 purpose with a large-diameter bearing 41 in front of the ribs 35. Internal grooves 42 in the collar are provided to accommodate the shaft ribs 30.

60 The drum is encircled by a brake-band 43, with friction lining 44, by which the drum is held against rotation in order to sustain the load, or released for lowering. The brake-band has reinforced end members 45 provided with perforations 46; and a spring 65 47 interposed between these members tends

to release the brake from the drum. The brake is supported by a rod 48, which extends from a screw 49 across the top of the brake chamber, through the perforated end members and the spring, into a bearing aperture 50 in the inner side wall of the chamber. The said screw occupies an internally screw-threaded opening 51 in the outer side wall of the chamber, and at its outer end carries a crank-handle 52, by manipulation 70 of which the operator effects lowering of the load. Thus, a partial turning movement of the handle in one direction causes the inner end of its screw to press upon the adjacent end member 45 sufficiently to clamp the 80 brake-band upon the drum, while similar movement in the opposite direction causes the screw to recede, permitting the brake to open and free the drum. In this way a simple construction and advantageous form 85 of control for the jack are secured.

The enclosing base-frame is advantageously constructed of two sections, a base section 53 and a standard section 54, with the annex 3 integral with the lower part of the 90 standard section and its outer wall 14 constituted as a removable cover-plate. The sections 53 and 54 have circular interfitting alining formations 55, 56 on their meeting parts, and are united by bolts 57; and the 95 rear opening of the annex is made circular to receive a circular alining shoulder 58 on the cover-plate, which is secured by bolts 59.

The operation will be briefly stated. Lifting is performed by ratcheting the main 100 shaft in the ordinary manner. At such time the brake 43 holds the drum 29 and consequently the disks 28 against rotation. During each lifting stroke the end-thrust pressure of the worm is removed from the collection of disks, so that the disks 27 can turn 105 freely; but as soon as the effort ceases the load tending to cause the jacking member to sink back moves the worm endwise slightly and re-applies the pressure to the lock, so that the disks 27 are held against 110 rotation by the frictional embrace of the disks 28, with the result that the load is automatically held. To lower, the operator moves the handle 52 so as to remove the 115 brake and permit the entire assemblage of disks and the drum to turn with the worm, so that the jack runs down by gravity. By manipulation of the handle the operator controls the lowering, checking and stopping of 120 the load, this manual regulation being the more effective because of the manner of supporting and operating the brake. In case of the brake being applied suddenly, the 125 heavy momentum is not instantaneously arrested with destructive effects, because of the property of the plane surfaces of the disk elements for relative slippage under such circumstances. Such yielding, it will be understood, is brief, because the load 130

thrust of the worm is always sufficient for holding, but it is enough to save the mechanism from breakage. Slipping practically does not occur at the conclusion of the lifting 5 strokes because the parts do not gather momentum, and the sink-back at such time need be no greater, and can be less, than that in the ordinary jack mechanisms.

The construction, it will be observed, is 10 very simple and compact, as well as efficient, the entire holding and self-lowering mechanism being on a single shaft or axis in the base, geared to the main lifting shaft. The broad base, stationarily supporting the operating 15 and controlling mechanism, the location of which confers a permanent low center of gravity and working fulcrum, and the small-head ram guided in the top of the standard, together insure stability and compel 20 jacking substantially in line with the main screw, and produce a jack which is advantageous for moving about and for transportation on the railroads.

The jack hereof will be perceived to bear 25 a specific relation to the generic invention of the Kopf and Schwerin Patent No. 1,329,665 of February 3, 1920, and to that of my prior Patent No. 1,321,456, dated November 11, 1919. I do not necessarily 30 limit myself to the particular embodiment and mode of control of the multiple disk device, as in a copending application I have disclosed another construction in which the restraining disks are permanently 35 anchored and means are provided for separating or removing the pressure between the members of the pile.

What is claimed as new is:

1. A self-lowering jack comprising a base 40 with a hollow standard rising therefrom, a ram slidably guided in the standard, a steep-pitch lifting screw rotatably supported on the base and extending upward within the ram, a horizontal lifting shaft in the base 45 geared to the lower part of the screw, a worm-wheel on said lifting shaft, a second shaft in the base bearing a worm meshing said worm-wheel and of such pitch as to be driven thereby, and holding and releasing means 50 applied to said second shaft.

2. A self-lowering jack comprising a base with a hollow standard rising therefrom, a ram slidably guided in the standard, a steep-pitch lifting screw rotatably supported 55 on the base and extending upward within the ram, a horizontal lifting shaft in the base geared to the lower part of the screw, a worm-wheel on said lifting shaft, a second shaft in the base bearing a worm meshing 60 said worm-wheel and of such pitch as to be driven thereby, a multiple friction disk device on said second shaft subject to the end-thrust of its worm under load, and means for controlling said device.

65 3. A self-lowering jack comprising a base

having a hollow standard rising therefrom, and an annex, a ram slidably guided in the standard, a steep-pitch lifting-screw rotatably supported on the base and extending upward within the ram, a main shaft in the 70 annex geared to the lower part of the screw, means for operating said shaft to lift the load, a worm-wheel on said shaft, a second shaft in said annex transverse to the main shaft and bearing a worm of a pitch to be 75 driven by said worm-wheel, a holding and releasing device on said second shaft in the upper part of the base annex, and a lowering control handle on the annex connected to said device. 80

4. A self-lowering jack having an enclosing supporting frame comprising a base section, a separate standard section, an annex integral with the standard section and having a circular rear mouth, and a cover plate having a circular shoulder fitting said mouth and an inwardly projecting bearing, in combination with a ram slidably guided in the standard section, a steep-pitch screw rotatably supported on the base section and 85 extending upward within the ram, a bevel gear on the lower part of the screw, a horizontal lifting shaft journaled in the bearing of said cover plate and carrying a bevel pinion on its inner end meshing the gear 90 on the screw, a worm-wheel on the lifting shaft between said pinion and bearing, a second shaft journaled in the annex, a steep-pitch worm on said second shaft meshing the worm-wheel, and means for holding 95 and releasing the worm. 100

5. In a self-lowering jack, a jacking member and mechanism adapted to run down under the load, including a worm-wheel in driven relation to the jacking member 105 and a worm meshing the worm-wheel and of a pitch to be driven thereby, a worm-shaft, an enclosure having a bearing for one end of said worm-shaft, an entrance opposite said bearing and a brake-chamber behind 110 said entrance, a cover plate for said entrance containing the other bearing for the worm-shaft, a multiple disk device on the worm-shaft within said brake-chamber, and a brake encircling said device. 115

6. In a self-lowering jack, the combination with a holding and lowering shaft and a steep-pitch worm thereon, of multiple-disk means comprising disks engaged with the shaft and disks alternating therewith, and a barrel wherewith the latter disks are engaged, an abutment, said barrel having a back formed with a central bearing opening and sustained against said abutment, and a thrust collar interposed between the worm and the disks and having a circular bearing cooperating with the open side of the barrel. 120

7. In a self-lowering jack, and in combination with a jacking member and mecha- 125

130

nism adapted to run down under the load, band, and a handle on the outer end of said screw.

20

5 9. A self-lowering jack comprising a base with a hollow standard rising therefrom, a ram slidably guided in the standard, a steep-pitch lifting screw rotatably supported on the base and extending upward within the ram, a horizontal lifting shaft in the base 25

geared to the lower part of the screw, a second shaft in the base, meshing gears on the lifting shaft and on said second shaft adapted to operate in the lowering operation and to create end thrust parallel to the second shaft, a multiple friction disk device on the axis of the second shaft subject to said end thrust, and means for controlling said device.

30

10 8. In a self-lowering jack, having a jacking member and mechanism adapted to run down under the load, an enclosure having a screw-threaded opening in its wall, holding and lowering means in said enclosure including a drum and a brake-band, a control screw in said threaded opening cooperating at its inner end with the brake-
